(57) **CLAIM**

The ornamental design for a perfume fountain, as shown and described.

DESCRIPTION

FIG. 1 is a top front perspective view of a perfume fountain with its front panel open.

FIG. 2 is a bottom rear perspective view of the perfume fountain of FIG. 1 with its front panel open.

FIG. 3 is a front elevation view of the perfume fountain of FIG. 1 with its front panel open.

FIG. 4 is a rear elevation view of the perfume fountain of FIG. 1 with its front panel open.

FIG. 5 is a left side elevation view of the perfume fountain of FIG. 1 with its front panel open.

FIG. 6 is a right side elevation view of the perfume fountain of FIG. 1 with its front panel open.

FIG. 7 is a top plan view of the perfume fountain of FIG. 1 with its front panel open.

FIG. 8 is a bottom plan view of the perfume fountain of FIG. 1 with its front panel open.

FIG. 9 is a top front perspective view of the perfume fountain of FIG. 1 with its front panel closed.

FIG. 10 is a bottom rear perspective view of the perfume fountain of FIG. 1 with its front panel closed.

FIG. 11 is a front elevation view of the perfume fountain of FIG. 1 with its front panel closed.

FIG. 12 is a rear elevation view of the perfume fountain of FIG. 1 with its front panel closed.

FIG. 13 is a left side elevation view of the perfume fountain of FIG. 1 with its front panel closed.

FIG. 14 is a right side elevation view of the perfume fountain of FIG. 1 with its front panel closed.

FIG. 15 is a top plan view of the perfume fountain of FIG. 1 with its front panel closed; and,

FIG. 16 is a bottom plan view of the perfume fountain of FIG. 1 with its front panel closed.

The broken lines and areas within depict portions of the perfume fountain that form no part of the claimed design.
